UNITED STATES PATENT OFFICE.

EUGENE WILCKE, OF DAYTON, OHIO.

PIPE-COLLAR.

1,379,233.

Specification of Letters Patent. Patented May 24, 1921.

Application filed May 14, 1919. Serial No. 297,117.

To all whom it may concern:

Be it known that I, EUGENE WILCKE, citizen of the United States, residing at Dayton, in the county of Montgomery and State of 5 Ohio, have invented certain new and useful Improvements in Pipe-Collars, of which the following is a specification.

My invention relates to pipe fittings and particularly to a split collar or ornamental 10 flange applicable to a pipe, rod or like member intermediate its ends.

The object of the invention is to provide such a collar or flange which will not only be cheap and economical in construction, 15 but will be efficient in use, easily and quickly applied, of pleasing appearance, and unlikely to get out of repair.

A further object of the invention is to provide means for securely holding a light 20 sheet metal collar or flange in place, and to further provide a convenient, simple, and easily operated closure for a split collar of the character mentioned.

With the above primary and other incidental objects in view as will more fully appear in the specification, the invention 25 consists of the features of construction, the parts and combinations thereof and the mode of operation or their equivalents, as herein- 30 after described and set forth in the claims.

Referring to the drawings, Figure 1 is a perspective view of the collar or flange forming the subject matter hereof applied to a pipe. Fig. 2 is a top plan view of the 35 collar in closed position and removed from the pipe. Fig. 3 is a bottom plan thereof also in closed condition. Fig. 4 is a bottom plan view of the collar in open position. Fig. 5 is a vertical sectional view thereof.

40 Like parts are indicated by similar characters of reference throughout the several views.

The collar and closure members shown in the drawing and hereafter referred to are 45 preferably produced from sheet metal by spinning operations, but may be made by stamping, pressing, or otherwise forming them. As shown in the drawing the device comprises a convex shell having a peripheral bead about its base and a second bead about its crown or inner circumference. The 50 particular shape or configuration of the device is immaterial and may be modified according to conditions of use and the taste 55 of the maker. The collar member 1 is cut away at one side as at 2 on substantially parallel lines intersecting the inner circumference of the collar member at substantially diametrically opposite points. The closure member 3 is of like shape and comprises a 60 segment of substantially like proportions, revolubly located within the collar member 1, and retained therein by clenching the peripheral bead 4 of the collar member 1 over the like bead 5 of the closure section 3. 65 Inclosed within the peripheral bead or rim of the closure member is a stiffening or reinforcing wire 6, the free ends 7 of which are bent inward and curved concentric with the central opening of the collar. The ends 70 of the wire are unattached and free to yield under pressure. Normally the free ends 7 of the wire extend upon arcs of slightly less diameter than that of the central opening 75 which therefor is overhung by these yieldings arms 7, as clearly shown in Figs. 2 and 3. When the outer or collar member 1 and inner or closure member 3 are turned to such relation that their open sides coincide as shown in Fig. 4, the assembled device is 80 easily slipped laterally into engagement with a pipe, column, rod or other such element, until the yielding arms 7 engage such member. It is to be understood that the yielding arms are curved about the inner circumference of the closure member opposite the 85 open side or cut away portion thereof. The pipe, column, rod or other member having been engaged within the bifurcation of the device, the closure member 3 and collar member 1 are relatively rotated until the closure member extends entirely across the opening of the outer or collar member as 90 shown in Figs. 1, 2 and 3. At such time the yielding arms 7 pressed outward by their 95 engagement with the pipe or other member exert such pressure thereon as will tend to hold the collar in its adjusted position and prevent rattle or chatter thereof due to vibration. It will be understood that the device is applied at a point removed from the 100 floor or wall sufficient to enable the operator to grasp the inner or closure member with his fingers in the bights or loops 8 to effect the relative rotation of the members 1 and 3, and that the adjusted device is thereafter shifted on the pipe to its final position adjacent to the floor or wall. The split collars as herein described may be made in a variety 105 of sizes and styles or shapes.

From the above description it will be apparent that there is thus provided a device of the character described, possessing the particular features of advantage before 5 enumerated as desirable, but which, obviously, is susceptible of modification in its form, proportion, detail construction and arrangement of parts, without departing from the principle involved or sacrificing 10 any of its advantages.

While the invention has been described in language more or less specific as to certain structural features, it is to be understood that the invention is not limited to the specific details shown, but that the means and construction herein disclosed comprise but one of several modes of putting the invention into effect and the invention is therefore claimed in any of its possible forms or 20 modifications within the legitimate and valid scope of the appended claims.

Having thus described my invention I claim:

1. In a device of the character described, 25 two relatively rotatable interconnected arcuate members, each having a lateral passage way, the open portions of the respective arcuate members being movable into and out of registry one with the other by the relative adjustment of said members.

2. In a device of the character described, an annular collar comprising two relatively 35 rotatable interconnected arcuate members each having a lateral opening and resilient gripping means normally overhanging the central opening of the collar.

3. In a device of the character described, an annular collar comprising two relatively 40 rotatable concentric arcuate members each having a lateral opening, and resilient pipe engaging arms normally overhanging the central opening of said collar.

4. In a device of the character described, 45 two concentric annular members relatively rotatable in relation one with the other, each member having therein a lateral opening to its inner orifice, the lateral openings of the respective members being shifted into and out of registry by the relative rotation of 50 the members.

5. In a device of the character described, the combination with an annular collar comprising relatively rotatable overlapping arcuate sections, of resilient means carried by 55 the collar and overhanging the central opening thereof to yieldingly engage a body passed through the opening.

6. In a device of the character described, 60 the combination with an annular collar comprising relatively rotatable overlapping arcuate sections, of resilient arms extending in the plane of rotation of the collar sections

adapted to yieldingly engage a body passed through the central orifice of the collar.

7. In a device of the character described, 65 the combination with an annular collar comprising relatively rotatable overlapping arcuate sections, of resilient means yielding in a plane parallel with that of the collar and carried thereby and adapted to engage a 70 body passed through the central orifice of the collar.

8. In a device of the character described, 75 an annular collar comprising two concentric relatively rotatable members, one of which is provided with a convex face, the other member having a concave face within which the convex face of the opposing member engages, each member having therein a lateral opening leading to the center of the 80 member, the openings of the respective members being shifted into and out of registry by the relative rotation of the members.

9. In a device of the character described, 85 an annular collar comprising two concentrically arranged concavo-convex substantially **C** shaped members nested one within the other and relatively rotatable, substantially as specified.

10. In a device of the character described, 90 an annular collar comprising two concentric relatively rotatable substantially **C** shaped members, substantially as specified.

11. In a device of the character described, 95 an annular collar comprising two concentric relatively rotatable substantially **C** shaped members, the periphery of one of said members being clenched over the periphery of the other member, substantially as specified.

12. In a device of the character described, 100 an annular collar comprising two concentric, relatively rotatable substantially **C** shaped members, and a resilient curviform arm the radius of which is less than the interior radius of the collar and carried by one of the 105 members, substantially as specified.

13. In a device of the character described, 110 two overlapping relatively rotatable collar sections, affording jointly a circular opening to receive a pipe or like body, each section having therein a radially disposed slot, leading to said central opening, the slots of the respective collar sections being movable into and out of registry one with the other by the rotation of said collar section to enable the 115 entrance of the pipe or like body to be closed.

In testimony whereof, I have hereunto set my hand this 9 day of May, A. D. 1919.

EUGENE WILCKE.
